United States Patent Office

Des. 191,868

Patented Dec. 5, 1961

191,868

WINDOW

Charles C. Paul, Franklin, and Norbert T. Kuypers, Warren, Mich., assignors to National Steel Corporation, a corporation of Delaware

Filed Mar. 3, 1961, Ser. No. 64,135

Term of patent 14 years

(Cl. D13—1)

FIG 1

FIG 2

FIG 3

FIG 4

FIG 5

FIG 6

FIGURE 1 is a perspective view of a window showing our new design as viewed from the left front of the window;

FIGURE 2 is an end view of the window of our invention;

FIGURE 3 is an elevational view of the rear of a window according to our invention;

FIGURE 4 is a section on the line 4—4 of FIGURE 1;

FIGURE 5 is a front elevation of a modified form of window according to our invention; and

FIGURE 6 is a front elevation of a still further modified form of window according to our invention.

We claim:

The ornamental design for a window, as shown and described.
